UNITED STATES PATENT OFFICE.

CHARLES E. GODLEY, OF DETROIT, MICHIGAN.

DESIGN FOR A VEHICLE LAMP.

Application filed June 24, 1922. Serial No. 2,811. Term of patent 14 years.

To all whom it may concern:

Be it known that I, CHARLES E. GODLEY, a citizen of the United States, residing at Detroit, in the county of Wayne and State of Michigan, have invented a new, original, and ornamental Design for Vehicle Lamps, Particularly Tail Lamps for Automobiles, of which the following is a specification, reference being had to the accompanying drawing, forming part thereof.

In the drawing Fig. 1 is a perspective view showing the front and Fig. 2 is a similar view showing the rear of a lamp embodying my new design.

I claim:

The ornamental design for a vehicle lamp, as shown.

CHARLES E. GODLEY.
